UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

COUNTERWEIGHTED SECTIONAL DOOR.

1,248,755.

Specification of Letters Patent.

Patented Dec. 4, 1917.

Application filed July 16, 1917. Serial No. 180,698.

To all whom it may concern:

Be it known that I, CHARLES C. TOMKINSON, a citizen of the United States of America, and a resident of Plainfield, Union county, and State of New Jersey, have invented certain new and useful Improvements in Counterweighted Sectional Doors, of which the following is a specification, reference being had to the accompanying drawings, forming a part thereof.

My invention relates to new and useful improvements in doors of the three section type and particularly to a counterweighting system therefor. More specifically it relates to a three-section door of which the central section is suspended by pivoted links and over opposite sides of which the lower and upper sections slide into registering positions. Doors of this general type are adapted to close large openings such as the doorways of warehouses, pier sheds and the like, and consequently are heavy structures. Their operation is difficult unless some suitable way of counterweighting them is provided. Heretofore no way has been known for counterweighting doors of this specific type and the particular object of this invention is to overcome this difficulty and to provide a simple and effective counterweighting system for such doors.

In order that my invention may be thoroughly understood I will now proceed to describe the same in the following specification and then point out the novel features thereof in appended claims.

Referring to the drawings:

Figure 1 is a sectional side elevation of a three-section door of the type to which this invention relates with my improvement connected therewith, the door being shown in its closed position.

Fig. 2 is a similar view of the same parts with the door shown in its open position.

Fig. 3 is a sectional plan view of some of the parts on a larger scale. The section in this figure is taken on the line 3—3 of Fig. 1.

Fig. 4 is an end elevation of a latch mechanism which appears in the other figures of the drawings.

Like characters of reference designate corresponding parts in all the figures.

10 designates a part of the structure of a building, 11 the part thereof which forms the lintel of a door opening, and 12 the side posts of the door opening. The latter as

shown somewhat in detail in Fig. 3, comprises a flat vertical member 13 which forms a track for a roller 34 and spaced therefrom a parallel roller guide 14.

The door comprises a central section 20 suspended by links 21 which are pivoted at 22 above the door opening and to brackets 23 on the upper corners of the central door section. 24 is a lower section and 25 an upper section. On each of the vertical edges 65 of the central section 20 are two channel irons 26 and 27 between the flanges of which are spaces in which slidably fit the flanges of angle irons 28 and 29 on the lower and upper door sections respectively. These 70 parts form guides for the lower and upper door sections and hold the three sections together.

Sheaves 30 are rotatively supported in the brackets 23 and chains or cables passing 75 over these sheaves are fastened to the lower corners of the upper door section at 31 and to the upper corners of the lower door section at 32. Brackets 33 on the lower corners of the lower door section support the rollers 80 34. Hoisting chains 35 are also connected to these brackets and run up to an overhead hoisting mechanism 36.

Counterweights 37 are attached to chains or cables which run up over sheaves 38 and 85 down to the lower corners of the central door section 20 to which they are attached at 39.

Short bars 40 project laterally from the central door section near the upper part 90 thereof and when the door is closed are engaged by latches 41 which are pivoted at 42 to the roller guides 14 and are pressed by springs 43 into latching position. 44 are release bars pivoted to the edges of the lower 95 door section at 45 and pressed by springs 46 in one direction against stop pins 48.

I will now describe the operation of this apparatus. An upward pull on the hoisting chains 35 will raise section 24 and this will 100 allow section 25 to run down. This movement will continue until the three door sections are in registering positions. Just as the lower section is about to reach the limit of its movement relative to the central section 20, the release bars 44 will raise the latches 41 and unlock the bars 40.

The relative movement of section 24 over section 20 is limited by a stop 16 affixed to the upper edge of section 20. Further up- 110

ward movement of the hoisting chains will result in the rollers 34 continuing their upward vertical movement but the three door sections will now be swung inwardly by the links 21 until they reach a horizontal position. During this part of the operation the counterweight 37 will move downwardly and assist in raising the door sections.

In closing the door the movement of chains 35 is reversed. First the door sections swing down until they reach a vertical position, when the latches 41 catch the bars 40. The release bars 44 being free to swing about their pivots against the action of springs 46 will prevent them from interfering with the latching operation. The lower section 24 is somewhat heavier than the upper section 25 so that as it descends from its position back of the central section 20 it will raise the upper section. The use of a latch arrangement makes it possible to have the weight 37 heavier than that of the door section 20, so that it will assist in raising all of the door sections.

I intend no limitations other than those imposed by the appended claims.

What I claim is:

1. A door comprising three sections, links pivotally suspending the central section from above the door opening, guide connections between the door sections to provide for a vertical telescoping movement of said sections, means for guiding vertically the lower part of the lower door section, a flexible connection between the upper and lower door sections for balancing said sections during their telescoping movement, and a counterweight for said sections connected with the lower part of the central door section.

2. A door comprising three sections, links pivotally suspending the central section from above the door opening, guide connections between the door sections to provide for a vertical telescoping movement of said sections for balancing said sections during their telescoping movement, means for guiding vertically the lower part of the lower sections, a counterweight for said sections connected with the lower part of the central door section, and means releasable by the telescoping movement of the door sections for holding said central door section in a vertical position.

3. A door comprising three sections, links pivotally suspending the central section from above the door opening, guide connections between the door sections to provide for a vertical telescoping movement of said sections, means for balancing said sections during their telescoping movement, means for guiding vertically the lower part of the lower section, a counterweight for said sections heavier than the central door section

connected with the lower part thereof, a latch for catching the central door section when it swings into vertical position, and a release bar on one of the other door sections for releasing said latch during the telescoping movement of the sections, said release bar being pivoted to prevent interference with the catching operation of the latch.

4. A door comprising three sections, links pivotally suspending the central section from above the door opening, the lower section being heavier than the upper section, guide connections between the door sections to provide for a vertical telescoping movement of said sections, sheaves at the upper corners of the central door section, means for guiding vertically the lower part of the lower door section, flexible connections between the upper and lower door sections running over said sheaves for balancing said sections during their telescoping movement, hoisting chains connected with the lower corners of the lower door section, and a counterweight for said sections connected with the lower part of the central door section.

5. A door comprising three sections, links pivotally suspending the central section from points near the upper corners thereof and points above the door opening, the lower section being heavier than the upper section, guide connections between the door sections to provide for a vertical telescoping movement of said sections, sheaves near the upper corners of the central section, rollers connected with the sides of the lower section near the lower part thereof, means for guiding said rollers vertically, hoisting chains connected with the lower section near said rollers, flexible connections running over said sheaves from the lower corners of the upper section to the upper corners of the lower section, and a counterweight for said section connected with the lower corners of the central section.

6. A door comprising three sections, links pivotally suspending the central section from points near the upper corners thereof and points above the door opening, the lower section being heavier than the upper section, guide connections between the door sections to provide for a vertical telescoping movement of said sections, sheaves near the upper corners of the central section, rollers connected with the sides of the lower section near the lower part thereof, means for guiding said rollers vertically, hoisting chains connected with the lower section near said rollers, flexible connections running over said sheaves from the lower corners of the upper section to the upper corners of the lower section, a counterweight heavier than the central section connected with the lower

corners thereof, pivoted latches at the sides of the central section, transverse bars projecting from the central section under said latches when the door is closed, and pivoted release bars on the lower section arranged to raise and release said latches during the telescoping movement of the sections and to swing to prevent interference with the

catching operation of the latches during the closing operation of the door.

In witness whereof, I have hereunto set my hand this 12 day of July, 1917. 10

CHARLES C. TOMKINSON.
